UNITED STATES PATENT OFFICE

2,097,163

ANIMAL STANCHION

Oscar E. Olson, Abbotsford, Wis.

Application March 24, 1937, Serial No. 132,779

2 Claims. (Cl. 119—147)

My invention refers to a permanent anchor means for animal stanchions, and it has for its object to provide a metallic sleeve, which is permanently cemented into the stanchion ridge of an animal stall, whereby the strap comprising one element of a lower stanchion shackle may be quickly and economically assembled or dismantled from the permanent sleeve, in the event of renewal, it being understood that this renewal of 10 the stanchion strap is effected without injury or cutting away of the cement ridge.

A further object of the invention is to provide this permanent anchor for the reception of a strap bolt, whereby the strain of the bolt, or 15 breakage due to strain of the stanchion ridge, is in effect eliminated.

A further object of my invention is to provide the anchor strap with means for adjusting the stanchion shackle backward or forward relative 20 to the concrete stanchion ridge, and evacuation trough, to compensate for varying lengths of the animal.

With the above and other minor objects in view, the invention consists in certain peculiarities of construction and combination of elements, 25 as hereinafter set forth with reference to the accompanying drawing and subsequently claimed.

In the drawing:

Figure 1 represents a fragmentary sectional elevation of the cement floor of an animal stall provided with a standard stanchion ridge, the same being shown equipped with an anchor sleeve and associated parts embodying my invention, certain of the said parts being in section to more 35 clearly illustrate structural features.

Figure 2 is an end elevation of the same, with parts broken away and in section, as illustrated by the dotted line 2—2 of Figure 1.

Figure 3 is a perspective view of one form of 40 anchor strap embodying the elements of my invention.

Figure 4 is a fragmentary side elevation of another form of anchor strap embodying the features of my invention, the same being partly 45 broken away and in section to illustrate structural features.

Figure 5 is a cross section of a fragment of cement floor, having projecting therefrom an anchor ridge carrying a sleeve, which is permanently cemented in said ridge, for the reception 50 of stanchion shackle equipment.

Referring by characters to the drawing, A represents the cement floor of the front or head portion of an animal stall, having extended upwardly 55 therefrom a rectangular anchor ridge B of stand-

ard type. The anchor ridge has embedded or cemented therein a plurality of metallic sleeves 1, there being only one of said sleeves illustrated. This sleeve extends transversely of the ridge, and has open ends flush with the side faces of said 5 ridge. Hence, due to its flush relation with the side walls of the ridge, there are no obstructions offered, and said sleeve, being a permanent part of the floor, can readily be used for attaching the desired shackle elements of a stanchion.

As best illustrated in Figures 1 and 2 of the drawing, a rectangular anchor strap 2 is fitted over the ridge, having legs 3—3 terminating with apertures, which, when the strap is properly adjusted, will align with the sleeve 1. The upper 10 stretch of the strap is provided with a plurality of companion sets of apertured ears 4—4, any pair of which are for the reception of a retaining bolt 5 for engagement with the lower link 15 of a chain 6, the same being suitably connected to the lower throat portions of any standard stanchion C, it being understood that the upper portion of the stanchion (not shown) is in swinging connection with an overhead element.

After adjustment of the stanchion strap 2, a 25 retaining bolt 1 is passed through the apertured strap legs, and loosely through the anchor sleeve 1, said bolt being provided with a head and the usual nut, whereby it is secured with relation to the assembled parts.

Thus it will be seen that the anchor strap is firmly held to the ridge, and that pull strain upon it is resisted by the connecting parts, to-wit the sleeve and bolt, anchored in the base of the ridge. In the event that any of the strap parts become 35 worn or broken, it is obvious that said defective strap can be quickly removed and replaced by simply manipulating the bolt 1, thus avoiding the difficult and expensive operation of renewal, which usually requires chipping away of some 40 portion of the cement ridge, whereby said ridge must be repaired or renewed.

Referring especially to Figure 4 of the drawing, the upper reach of the strap 2 is illustrated as having a plurality of apertures 8 therein for the selective reception of bolts 9, which bolts carry the shoe portion 10 of an apertured set of ears 11. By this means the ear 11 can readily be adjusted transversely to compensate for short or long animals, or it can be renewed in the event 50 of breakage.

From the foregoing description it is understood that while I have shown and described specific structure, I may vary certain of the parts within the scope of the claims.

I claim:

1. A stanchion shackle mechanism comprising a metallic tube transversely embedded into a concrete stanchion ridge, a strap nested about the ridge having apertured legs in alinement with said tube, a bolt passing through the tube for confining the legs, and a set of apertured ears provided with a foot engaging the upper stretch of the strap, said strap having a plurality of apertures for adjustment of the foot portion of the ears, and bolts for securing the same to the upper stretch of the strap, the bolts being passed through the foot of said ears and a selected pair

of the strap apertures, whereby the shackle ears are predeterminedly adjusted with relation to the strap.

2. A stanchion shackle mechanism comprising a metallic tube transversely embedded in a concrete stanchion ridge, a strap straddling the ridge and provided with depending legs having apertures alined with said tube, a bolt passing through the tube and said apertures for confining the legs, and means carried by the upper stretch of said strap for adjustable attachment of the stanchion shackle.

OSCAR E. OLSON.
